FACING BRICK

Andrew M. Matyas, 1642 North Road SE., and John A.
Matyas, 2655 Brandywine SE., both of Warren, Ohio

Filed Mar. 12, 1963, Ser. No. 73,938

Term of patent 3½ years

(Cl. D18—2)

We claim:

The ornamental design for a facing brick, substantially as shown.
